UNITED STATES PATENT OFFICE.

HERMANN DIERNHOFER, OF GROSSSCHOENAU, GERMANY.

PROCESS FOR PRODUCING PHOTOGRAPHS IN NATURAL COLORS ON PAPER.

No Drawing.

Application filed January 14, 1925. Serial No. 2,459.

To all whom it may concern:

Be it known that I, HERMANN DIERNHOFER, a citizen of the German Empire, residing at Grossschoenau, Saxony, Germany, No. 787 Blumenstr., have invented certain new and useful Improvements in a Process for Producing Photographs in Natural Colors on Paper, of which the following is a specification.

10 This invention relates to a process for producing photographs in natural colors on paper by transferring dissolved colors one after the other from several gelatinous layers to a sheet of paper provided with a 15 receiving gelatinous layer. The processes hitherto in use, as, for example, pinatypy, proceed by printing the several plates containing part prints in color on top of each other on a gelatinized paper, the process 20 being perfect only if all part prints are in perfect register with each other. This true register, however, has not yet been obtained in the processes hitherto in use, and a perfectly registered picture in natural colors is 25 the exception rather than the rule. The difficulties connected with most processes hitherto in use and particularly with the pinatypy process are as follows:

1. The colors from the printing plates are 30 immediately absorbed by the transfer paper when coming in touch with each other and usually before the outlines of the picture are in true register. The result is that the second and following part prints are not 35 in true register with the preceding ones.

2. Pinatypy colors show a tendency of 40 growing indistinct and merging into one another when subjected to the influence of water or moist air for a longer period so that the outlines disappear. The technique of pinatypy does not permit to work fast enough to overcome these harmful influence of water and moist air.

3. When thoroughly squeezing out the 45 water kept between the layers, particularly if the latter consist of soft gelatine or if excessive reliefs are formed by the pressure exerted on the gelatine soaked with water there are easily produced a large number of 50 small air bubbles, particularly at higher temperatures, which are hard to eliminate. The presence of these air bubbles, however, prevents the uniform transfer of the colors to the paper and thus a good reproduction.

The present invention does away with all 55 these drawbacks. It ensures, on the one hand, a true register of the various part prints and, on the other hand, a perfect and intimate contact between printing plate and sheet on the entire surface while removing all excess water. The nature of 60 this invention consists in obtaining a perfect register of the outlines of printing plate and paper picture before there is any chance of the colors being transferred to the paper. 65 This can be done in the following two ways:

1. All part pictures are either printed one after the other on one single gelatine layer of a paper or 70 2. A special layer is placed on the preceding print before the next part print is transferred. The first part print is made in the usual manner in both processes.

The outlines of the picture are brought in 75 true register before inking the plate. The gelatine paper holding the first part print is immersed in water for a moment and immediately taken out again, whereupon the excess water on the layer side is removed by wadding; the paper is then made to float 80 on water with the layer side up to get its full extension owing to soaking, while care must be taken that the gelatine side does not touch the water. While the paper is thus 85 fully expanded the layer side is almost dry so that the paper can be placed layer for layer on the dry printing plate and the outlines of paper and plate brought in true register by shifting. If true register has 90 been established, the paper picture is held in position on one edge of the plate by clamps etc.; it is advisable to make allowance for this fastening by making the edge or margin of the plate wider.

The paper is then lifted up, the plate is 95 inked and printing continued in the usual manner.

The already mentioned harmful influence of water and moist heat upon printing plate and paper is eliminated by giving the 100 paper the preparatory treatment described above. The gelatinous layer will thus acquire the highest degree of adhesion so that it becomes at once attached to the printing plate layer when paper and plate are 105 brought into contact. In this manner the gelatinous layer will absorb ink without moving in the least, and it is difficult to

move it on the plate. The small amount of water remaining between the layers can be squeezed out in the usual manner quickly and safely. As the paper in the new process sticks firmly and almost immovably to the plate, owing to adhesion, any shifting of the print as hitherto experienced is absolutely impossible. The water squeezed out of the paper remains outside the gelatinous layers of print and plate and is therefore harmless. The influence of the water upon the already finished part pictures is reduced to a minimum of a few seconds so that the colors printed thereon cannot be damaged or otherwise influenced. Clear definition is thus maintained.

After establishing a true register of the outlines of the picture in the manner described a sheet of dry blotting paper is placed on the printing plates, if the gelatinous layer should be excessively softened by too high temperatures or too warm water, the plate is then kept with the sheets of paper for a period of 5-15 minutes in a cooler room. This will cause the gelatine of the printing plate to get denser and harder, while the excess water emitted will be absorbed by the blotting paper so that work can be continued in the warmer room later on.

The pinatypy and other processes employing wet paper for printing part pictures do not permit to find out before the part paper picture blends with the printing plate whether the paper picture has the degree of expansion due to moisture required for producing a picture of exactly the same size as the plate picture, while the present invention establishes the perfect register between paper picture and plate before their union. The paper of the print, by adding or removing water, can thus be made to have the size necessary to produce exactly the same size of paper part picture and plate picture even if several prints are made. It is thus possible to produce sharply defined pictures.

The other form of the invention consists in covering the first part print, which is fixed at once and dried by means of wadding etc. with a second thin layer of gelatine for the reception of the second part print. This dried layer thus protects the ink of the first part print against the influence of water and a contact with the printing plate of the second part print so that the union of the first part print with the printing plate can take place without any danger of squashing or otherwise damaging the ink of the first part print while the paper is fully capable of receiving the ink from the second part plate.

Paper picture and printing plate are brought into true register before the plate is inked, as described above.

In the same manner each additional part print is handled so that each part print has a gelatinous layer of its own.

By employing this second process any possible harmful influence of one of the prints upon the preceding prints is perfectly eliminated. Particularly advantageous is the following method of working. After fixing and superficially drying the first part print by absorbing excess moisture by wadding, place a focussing screen in a basin with water with its dull side up, let the print float on the water above the screen until the air has removed all excess water from the gelatinous surface which is then no longer sticky and cause the print to lie smoothly on the screen by lifting the latter. Then, remove the focussing screen with the print from the water so as to permit it to run off without, however, flowing over the layer side, squeeze out the excess water contained between the focussing screen and the picture simply by placing celluloid foil on the surface of the picture and several sheets of blotting paper on top of it and projecting over it. By passing a smoothing bone over the paper from the center to the edges the water is squeezed towards the edges of the picture and absorbed by the blotting paper projecting over the foil. The picture is thus pressed on the focussing screen perfectly smoothly, and the latter is now arranged perfectly horizontally, with the print up. It is then covered with a correspondingly diluted solution of printing plate gelatine in a thin layer, while care should be taken not to let the solution run over the edges on the focussing screen, and the layer is then left for about half an hour until it is hard enough. The print can then be removed from the focussing screen and dried, preferably by suspension.

All other manipulations are exactly like those described in connection with process 1.

When bringing the outlines of the picture in true register before inking the plate, it is advisable before lifting the print to ink the plate to insert a celluloid sheet etc. of ample dimensions to protect the print after it has been lifted up against ink or water splashes or other damages due to making ready.

Having described my invention for the above cited application for Letters Patent in the specification sworn at Dresden on December 24, 1924, now, what I claim as new and desire to secure by Letters Patent of the United States is:

1. The process for producing colored photographs on a sheet by transferring dissolved colors one after the other from several printing plates each provided with a gelatinous layer to a sheet provided with a receiving gelatinous layer by placing the sheet on the printing plate layer on layer after protecting the color of the print

already applied to the sheet against being impaired, by then shifting the sheet on the plate until exact register of the outlines of the sheet and plate is reached, before there

5 is any chance of the color being transferred to said sheet, and by printing afterwards in the usual manner.

2. The process for producing colored photographs on a sheet of paper by transferring dissolved colors one after the other from several printing plates with gelatinous layers to a sheet of paper provided with a gelatinous layer all part prints being obtained in perfect register with each other 10 15 20 25

by immersing the gelatine paper holding the first print in water for a moment, by then removing the excess water on the layer side, by further placing the paper with its layer which is almost dry on the dry printing plate for the next print, layer on layer, and bringing the outlines of said paper and said plate in true register by shifting, whereupon the paper picture is fixed to said printing plate on one edge and lifted up with the other parts, then said plate is inked and printing continued in the usual manner.

3. The process for producing colored photographs on a sheet of paper by transferring dissolved colors one after the other from several printing plates with gelatinous layers to a sheet of paper provided with a gelatinous layer all part prints being obtained in perfect register with each other 30 35 40 45

by immersing the gelatine paper holding the first print in water for a moment, by then removing the excess water on the layer side, by further placing the paper with its layer which is almost dry on the dry printing plate for the next print, layer on layer, and bringing the outlines of said paper and said plate in true register by shifting, whereupon the paper picture is fixed to said printing plate on one edge and lifted up with the other parts, then the paper sheet is covered by a protecting sheet and the plate is inked and the printing continued in the usual manner.

4. The process for producing colored photographs on a sheet of paper by transferring dissolved colors one after the other from several printing plates with gelatinous layers to a sheet of paper provided with a gelatinous layer all part prints being obtained in perfect register with each other 50 55 60 65 70

by immersing the gelatine paper holding the first print in water for a moment, by then removing the excess water on the layer side, and making it float on water with the layer side up to fully expand the paper with its layer, by then placing the paper with its layer which is almost dry on the dry printing plate for the next print, layer on layer, and bringing the outlines of said paper and said plate in true register by shifting, whereupon the paper picture is fixed to the

printing plate on one edge and lifted up with the other parts, then the plate is inked and the printing continued in the usual manner.

5. The process of producing colored photographs on a sheet of paper by transferring dissolved colors one after the other from several printing plates with gelatinous layers to a sheet of paper provided with a gelatinous layer all part prints being obtained in perfect register with each other by immersing the gelatine paper holding the first print in water for a moment, by then removing the excess water on the layer side, by further placing the paper with its layer which is almost dry on the dry printing plate for the next print, layer on layer, and bringing the outlines of said paper and said plate in true register by shifting, by changing the degree of moisture of the paper for regulating the expansion of said paper, whereupon the paper picture is fixed to the printing plate on one edge and lifted up with the other parts, then the plate is inked and the printing continued in the usual manner. 70 75 80 85 90

6. The process for producing colored photographs on a sheet by transferring dissolved colors one after the other from several printing plates with gelatinous layers to a sheet provided with a receiving gelatinous layer all part prints being obtained in perfect register with each other by bringing the outlines of the printing plate for the following part print by shifting into perfect register with those of the preceding part print on said sheet, after having covered said preceding part print with a thin layer of gelatine for the reception of the following print, whereupon the paper picture is fixed to the printing plate on one edge and lifted up with the other parts, then the plate is inked and the printing continued in the usual manner. 95 100 105

7. The process for producing colored photographs on a sheet by transferring dissolved colors one after the other from several printing plates with gelatinous layers to a sheet provided with a receiving gelatinous layer all part prints being obtained in perfect register with each other by bringing the outlines of the printing plate for the following part print by shifting in perfect register with those of the preceding part print on said sheet, after having covered said preceding part print with a thin layer of gelatine for the reception of the following print, by placing the moist paper sheet with at least one part print thereon on the dull side of a focusing screen, the layer up, covering it with a celluloid foil and then with at least one sheet of blotting paper on top of said foil projecting over it and squeezing the excess water from the print paper by pressing the sheets and foil against said 110 115 120 125 130

focusing screen into the edges of the blotting paper, whereupon the paper picture is fixed to the printing plate on one edge and lifted up with the other parts, then the plate is inked and the printing continued in the usual manner.

8. The process for producing colored photographs on a sheet of paper by transferring dissolved colors one after the other from several printing plates with gelatinous layers to a sheet of paper provided with a gelatinous layer all part prints being obtained in perfect register with each other by immersing the gelatine paper holding the first print in water for a moment, by then removing the excess water on the layer side, by further placing the paper with its layer which is almost dry on the dry printing plate for the next print, layer on layer, and bringing the outlines of said paper and said printing plate and said paper picture fixed to each other are cooled, after which said plate is inked and printing continued in the usual manner.

20 and bringing the outlines of said paper and said plate in true register by shifting, whereupon the paper picture is fixed to said printing plate on one edge and lifted up with the other parts, then cooling said

25 printing plate and said paper picture fixed

to each other, after which the plate is inked and the printing continued in the usual manner.

9. The process for producing colored photographs on a sheet of paper by transferring dissolved colors one after the other from several printing plates with gelatinous layers to a sheet of paper provided with a gelatinous layer all part prints being obtained in perfect register with each other by placing the moist paper with its layer which is almost dry on the dry printing plate for the next print, layer on layer, and bringing the outlines of said paper and said plate in true register by shifting, whereupon the paper picture is fixed to said printing plate on one edge and lifted up with the other parts, a sheet of blotting paper is laid upon said printing plate and then said printing plate and said paper picture fixed to each other are cooled, after which said plate is inked and printing continued in the usual manner.

In testimony whereof I affix my signature.

HERMANN DIERNHOFER.
